UNITED STATES PATENT OFFICE.

FLORENCE M. JOHNSON, OF NAMPA, IDAHO.

ARTICLE-SUPPORTING ATTACHMENT FOR IRONING BOARDS.

Application filed March 27, 1924, Serial No. 702,360. Renewed August 16, 1927.

This invention relates to ironing board attachments and particularly to an attachment having the character of a supporting member extending parallel to the ironing board and designed for supporting sheets, table cloths and other large articles while they are being ironed.

In ironing table cloths, sheets, curtains and such like articles whose length makes it very difficult to handle, it is necessary either to drop the clothes down into a clothes basket as the cloth is ironed, spread papers or sheets on the floor and drop the cloth down on the paper or sheet as it is ironed or drape the cloth over the back of a chair or something of that sort. None of these three methods keep the cloth from wrinkling again and a basket or chair takes up a good deal of room. Furthermore, the cloth often gets soiled if it does not, in descending, rest upon the paper or sheets which have been laid upon the floor.

It is the object of my invention to provide a device which may be readily applied to any ordinary type of ironing board and which when unfolded or projected constitutes a longitudinally extending supporting bar or member upon which the cloth as it is ironed may be hung in large folds, the cloth being retained thereon by means of clothes pins or the like.

A further object is to provide a device of this character which may be retracted beneath the board under ordinary circumstances and when the board is being used for ironing other articles than sheets and the like, which device will not be in the way or prevent the ordinary use of the ironing board and which will not prevent padding being attached to the ironing board if desired.

My invention is illustrated in the accompanying drawings wherein:

Figure 1 is a side elevation of an ironing board having my attachment applied thereto, with the attachment in folded position;

Figure 2 is an elevation of the ironing board as in Figure 1, but with the attachment shown as in use;

Figure 3 is an end elevation of the ironing board with the attachment extended;

Figure 4 is an end elevation showing the manner in which the attachment is used for

a relatively wide sheet, the member 11 being partly in section;

Figure 5 is a fragmentary perspective view of one of the cleats 11.

Referring to these drawings it will be seen that the ironing board 10 is of any suitable or ordinary shape and that upon the bottom of the ironing board are fastened by screws, nails or other attaching means, the transversely extending cleats 11. These cleats are each formed to provide a longitudinally extending aperture or passage 12 and I have illustrated this passage 12 as being formed by a groove in the cleat 11 on the outside face of the cleat, this groove being covered for its length by a metallic plate 13. I do not wish to be limited to this however. The plate 13 extends only part way along the cleat and just beyond the plate 13 there is formed an upwardly extending recess 14 which intersects the groove 12. The opposite end of the cleat from the plate 13 is also formed with a recess 15 which intersects the groove, this recess being formed by reducing the length of the base of the cleat. Between the upwardly extending recess 14 and the recess 15 the wall of the recess 12 overhangs, as shown in Figure 5.

Disposed within the groove 12 is a metallic rod 16 constituting a supporting member, one end of which is formed with an angularly bent arm 17, this arm terminating in a hook 18. The opposite end of the rod 16 is formed with a relatively short angularly bent arm 19 constituting a stop. The rod 16 is of sufficient length to permit it to be shifted longitudinally through the groove 12 so as to bring this stop or arm 19 either into the keeper or recess 14 or into the keeper or recess 15 as desired. Detachably engaged within the hooks 18 is a relatively small diametered coil contractile spring 20 having eyes at its extremities which may be engaged with these hooks. It will be seen that when it is desired that the arm 19 shall stand upright, the rod 16 is drawn forward and the angular end is engaged in the recess 14, thus holding the rod in an approximately upright position against further movement and locking it against reverse movement. When it is desired to shift the support formed by the members 16 inward to re-

tracted position, each rod 16 is turned slightly to carry the angular end 19 out of the recess 14, it is then shifted along the groove 12 until it reaches the recess 15, and at this point the rods 16 may be turned over so as to cause the arm 17 to be disposed in a horizontal position, as shown in Figure 1, the angular ends 19 of the rods then being disposed behind the end of the recess 15 so that they cannot be pulled out without turning the arm 17 to a vertical position again.

Under ordinary circumstances the attachment is entirely disposed beneath the ironing board 10 and to this end the rods 16 are shifted fully inward and the arms 17 are turned so as to carry the hooks towards each other to reduce the tension on the spring 20. When it is desired to use the attachment the spring 20 is detached at one end from one of the hooks 18 and the spring supports are turned over in opposite directions. They are then pulled outward until the arm or stop 19 strikes against the edge of the metal bar 13 and slips into the recess 14. The spring is again attached to one or both arms 17 and there is provided a long and strong wire support extending parallel to the edge of the ironing board and to which the article to be ironed is held by means of clothes pins or any other fastening device. This supporting member 20 is disposed on the opposite side of the board from the person who is ironing. If the cloth to be ironed is wide it is folded once lengthwise. One end of the cloth is ironed across and then moved forward and attached to each end of the wire or support 20 by clothes pins, preferably the ordinary spring clothes pins. The cloth is then, as it is ironed, moved forward and drops down between the wire 20 and the ironing board until it just misses the floor. If part of the cloth still remains unironed the cloth is slid over the wire and fastened with clothes pins from underneath. Then the cloth can be dropped down on each side of the wire in a double fold and still be kept smooth and held firmly in place. It will be understood, of course, that there are many ways of handling a cloth so that a four yard cloth or sheet may be readily ironed in one length and without folding. The cloth is, of course, reversed and the other side ironed in the same way, or if one prefers the cloth may be doubled crosswise and ironed that way.

This device will not interfere with the folding of the board in case a folding ironing board is used nor with the use of a built-in ironing board, as the device itself is entirely out of the way and on the bottom of the board and does not increase the normal width of the board. Neither does this device interfere with the use of a pad or cover, as plenty of room is allowed for the

pad or cover, nor does this device interfere with pad covers that lace back and forth across the under surface of the board.

In the drawings I have illustrated the ironing board as being supported by trestles A, and obviously these trestles might be made as part of the ironing board or they may be made separately therefrom and the ironing board rest thereon or on any other suitable support.

While I have illustrated a particular form of my device, I do not wish to be limited thereto as it is possible that many minor details might be changed without departing from the spirit of the invention.

What I claim is:—

1. The combination with an ironing board, of means for supporting large articles when being ironed comprising two supporting members mounted upon the under face of the board for sliding movement laterally of said board into a projected position or into a retracted position and entirely beneath the board, said supporting members each being right angular in form to provide a laterally extending arm at the outer end and a horizontally extending element connected at its ends to the upper ends of the arms and projectable or retractable therewith, said supporting members being oscillatable to carry said arms into a plane parallel to the plane of the ironing board or into an upwardly projected position, and means to hold said arms in said last named position.

2. The combination with an ironing board, of means for supporting large articles when being ironed comprising supporting members mounted upon the lower face of the board for lateral movement into a projected position or a retracted position entirely beneath the board and a longitudinally extending coil spring element having its extremities engaged with said supporting members.

3. The combination with an ironing board, of means for supporting large articles while being ironed comprising supporting members slidably and pivotally mounted upon the under side of the board and slidable from a retracted position entirely beneath the board to a projected position beyond the edge of the board, said members having arms at one end and a coil contractile spring element engaged at its extremities with said arms and shiftable with the supporting members.

4. The combination with an ironing board, of means for supporting large articles while being ironed comprising cleats attached to the lower face of the board, rods shiftable and oscillatably mounted in said cleats, each rod being formed at one end with an arm having a hook and at its other end with an arm constituting a stop, the cleats being formed with keepers with which said stops

are adapted to engage when the arms are projected and turned outward away from each other and a coil contractile spring detachably engaged at its extremities with said

5 arms.

5. The combination with an ironing board, of means for supporting large articles while being ironed, comprising cleats attached to the lower face of the board, each having a 10 longitudinally extending passage, a rod oscillatably and slidably disposed in each passage, each rod at one end being formed with a relatively long arm having a hook at its extremities, the opposite end of each rod 15 being formed with a relatively short arm constituting a stop, each cleat being formed with a keeper with which said stop arm is adapted to engage when the rods are shifted outward to carry the first named arms beyond the edge of the ironing board and ro-

tated to shift the first named arm in a position directed away from each other and a coil spring detachably engaged with the hooks on said arms and projectable or retractable with said rods.

25

6. The combination with an ironing board, of means for supporting large articles while being ironed, comprising supporting members slidably and rotatably mounted upon the under face of the board, each of said members having an arm provided at its end with a hook, a coiled contractile spring engaged with the said hooks, and means for holding the supporting members in projected position with their arms extending upward and hooks facing away from each other to thereby place tension on the spring.
